UNITED STATES PATENT OFFICE.

MAX ROBIN, OF NEW YORK, N. Y.

DESIGN FOR A SUSPENDING-HOOK.

SPECIFICATION forming part of Design No. 32,121, dated January 23, 1900.

Application filed December 20, 1899. Serial No. 741,063. Term of patent 7 years.

To all whom it may concern.

Be it known that I, MAX ROBIN, a citizen of the United States, and a resident of the city of New York, borough of Manhattan, in the county and State of New York; have invented and produced a new and original Design for a Suspending-Hook, of which the following is a full, clear, and exact description.

Reference is to be had to the accompanying drawing, forming a part of this specification, in which the figure is a perspective view of a hook, showing my design.

The design for a suspending-hook consists in the parallel members connected at the upper end by a curved portion, the sides of which extend out beyond the plane of the par-

allel members, and a portion extended outward at an angle from the lower end of one of the parallel members and having a depending hook-shaped end.

Having thus described my invention, I claim as new and desire to secure by Letters Patent—

The design for a suspending-hook as herein shown and described.

In testimony whereof I have signed my name to this specification in the presence of two subscribing witnesses.

MAX ROBIN.
